INSIDE PIPE CUTTER

Robert D. Brannon, Sulphur, La., and Hall G. Moore, Beaumont, Tex.

Application September 19, 1935, Serial No. 41,268

5 Claims. (Cl. 164—0.7)

This invention relates to an inside pipe cutter.

An object of the invention is to provide a cutter of the character described adapted to cut pipe, in a well bore, by rotation.

5 In well drilling operations the well pipe sometimes becomes stuck in the bore and cannot be withdrawn as a unit and hence must be cut into sections and removed a section at a time. It is an object of this invention to provide a cutter for that purpose.

Another object of the invention is to provide a pipe cutter of the character described having radially movable blades, or bits, normally held in retracted position and equipped with means capable of being actuated by the rotation of the operating string to gradually force said blades into active or pipe cutting position and to thereafter automatically release the blades to permit them to move into inactive position after the pipe has been severed.

A further object of the invention is to provide an inside pipe cutter having radially movable cutter blades mounted in a cutter body and normally held retracted with an expanding mandrel 25 mounted in the body and gearing also mounted in the body and arranged to be operated by rotation of the operating string to effect the expansion of the blades or bits into active or cutting position, said gearing being effective, by 30 continued rotation of the string, to release the mandrel from the cutters and to permit the cutters to move into inactive position, released from the pipe.

With the above and other objects in view, the 35 invention has particular relation to certain novel features of construction, operation and arrangement of parts, an example of which is given in this specification and illustrated in the accompanying drawing, wherein:—

40 Figure 1 shows a vertical sectional view of the cutter, shown in inactive position in the pipe to be cut.

Figure 2 shows a cross sectional view taken on the line 2—2 of Figure 1.

45 Figure 3 shows a cross sectional view taken on the line 3—3 of Figure 1.

Figure 4 shows a cross sectional view taken on the line 4—4 of Figure 1, and

50 Figure 5 shows a cross sectional view taken on the line 5—5 of Figure 1.

Referring now more particularly to the drawing wherein like numerals of reference designate similar parts in each of the figures, the numerals 1, 1 designate the complementary sections of the cutter body, said body being cylindrical in gen-

eral contour. The lower end of the body is reduced and externally threaded to receive the collar 2 which is screwed thereon to secure the lower ends of the body sections together. The numeral 3 designates the cutter head which is also cylindrical in general contour and whose lower end is threaded onto the reduced outwardly threaded upper end of the cutter body whereby the upper ends of the body sections are also secured together. Each section of the body has the dowel pins as 4, 4 as well as the sockets 5, 5, the pins of one section fitting into the sockets of the other to properly align the body sections preparatory to permanently securing them together.

5 The upper end of the head 3 is connected to an 15 operating string of pipe as 6, which extends to the ground surface and whereby the tool may be operated. The operating string is tubular and flushing fluid may be forced down through it and this fluid passes on through the channels 7, 7 20 of the head whereby a cooling and flushing fluid may be supplied to the cutter blades hereinafter referred to.

The head 3 has oppositely disposed longitudinal slots 8, 8 wherein are located the blade carriers 9, 9 which are pivoted on the cross pins 10, 10. The upper ends of the blade carriers are seated against coil springs 11, 11 which hold said upper ends outwardly and the lower ends of the carriers have the outwardly directed blades or 25 bits 12, 12 adapted to cut the pipe 13 wherein the cutter is to operate.

30 At the lower end of the head there is a shaft 15 having an enlarged head 16 which is fitted into an internal recess 17 in the lower end of the head and this shaft extends axially beneath the head and through an axial bearing 18 in the anchor block 19 beneath. The upper end of the shaft 15 is reduced forming a downwardly facing shoulder 20 which abuts the upper end of the block 19 and 35 screwed onto the lower end of the shaft 15 is the clamp nut 21 which may be screwed up tightly against the block 19 whereby said block will be securely clamped on the shaft 15 against turning thereon. The head 16 of the bolt 15 is shaped 40 so as to permit the cutter body to turn thereon and the upper end of said head 16 has a polygonal recess 22 therein.

45 Mounted in the block 19 are the radially movable pipe gripping members 23 whose outer sides are slightly concaved to present sharp edges to the pipe 3 so as to more effectively grip said pipe and the gripping members are held yieldingly in engagement with the pipe by the coil springs 24 50 against which they are seated.

The upper end of the cutter body has a deep socket 25 in which the conical shaped mandrel 26 is located. This mandrel is fastened to the upper end of the rod 27 which works through the stuffing box 28 in the body and the lower end of the rod 27 is pivotally connected to the upper end of the connecting rod 29. The other end of this rod is eccentrically and pivotally connected to the spur gear 30 which is fixed on the stub shaft 31 and this stub shaft is mounted to rotate in the bearing 32 in one of the sections 1. Beneath the gear 30 and mounted in suitable end bearings in the sections 1, 1 there is a transverse shaft 33 and fixed on this shaft 33 there is a spur gear 34 in mesh with the gear 30 and the worm gear 35, the latter being in mesh with the screw gear 36. This screw gear is fixed on a vertical stub shaft 37 whose lower end is fitted into, and shaped to conform to, the socket 22.

In operation the cutter is let down into the pipe 13 to the desired point. Thereupon the operating string 6 is rotated causing the head 3 and the cutter body to rotate with it. The anchor block 19 and shaft 15 will be held stationary, or against rotation, by the gripping members 23 and the shaft 31 will also be held stationary. Therefore, the rotation of the cutter body will impart a rotation to the gears 35, 34 and 30. This will operate through the connecting rod 29 to impart an upward movement to the rod 27 and mandrel 26 gradually forcing the cutters 12 outwardly and placing the springs 11 under compression. As the cutters 12 are gradually forced outwardly they are also rotated, and they will come into contact with and gradually sever the pipe 13. The gear ratio is such that upon the pipe 13 being severed the mandrel 26 will start its downward movement and the springs 11 will operate to retract the cutters out of contact with the pipe. Thereafter a suitable fishing tool or spear, carried by the operating string, may be engaged with the cut off section and said section removed with the cutter from the well; or when the cut is made the cutting tool may be withdrawn and fishing tool lowered into the well and engaged with the cut off section and the latter removed.

The drawing and description disclose what we now consider to be a preferred form of the invention by way of illustration only, while the broad principle of the invention will be defined by the appended claims.

What we claim is:

1. An inside pipe cutter adapted to cut by rotation and comprising a cutter body, an outwardly movable cutter associated with the body, a mandrel operative against the cutter and movable into one position to effect outward movement of the cutter and into another position to release the cutter, means for moving the cutter inwardly to inactive position upon such release, gearing on the body, means gripping the pipe to be cut and effective to operate the gearing upon rotation of the body and a connecting rod between the gearing and mandrel through which the mandrel is alternately moved to active or released positions.

2. A pipe cutter comprising an anchor, means thereon arranged to grip a pipe in which the cutter is located to hold the anchor against rotation, a rotatable cutter body connected to the anchor, means for rotating said body, outward-

ly movable cutters associated with the body, means normally holding the cutters retracted, a mandrel movable into one position against the cutters to actuate the cutters outwardly into active position and movable into another position to release the cutters to permit retraction thereof, gearing on the body, a connecting rod connecting the gearing and mandrel, and adapted to move the mandrel, and means connected with said anchor and gearing whereby the gearing is operated upon rotation of the cutter body.

3. A pipe severing device adapted to cut by rotation and shaped to be inserted into a pipe, in a well, to be cut and comprising an anchor, pipe-gripping means on the anchor, a body rotatable relative to the anchor, gearing housed within the body and operatively connected with the anchor whereby said gearing will be driven upon rotation of the body relative to the anchor, cutting means associated with the body and movable outwardly into cutting relation with the pipe, means normally acting to retract said cutting means into inactive position, a conical shaped actuator having a smooth surface and operatively connected with the gearing and arranged to be actuated thereby into active position to move said cutting means outwardly and into released position to permit retraction of the cutting means, alternately.

4. A pipe severing device adapted to cut by rotation and shaped to be inserted into a pipe, in a well, to be cut and comprising an anchor, pipe-gripping means on the anchor, a body rotatable relative to the anchor, gearing housed within the body and operatively connected with the anchor whereby said gearing will be driven upon rotation of the body relative to the anchor, cutting means associated with the body and movable outwardly into cutting relation with the pipe, means normally acting to retract said cutting means into inactive position, an actuator having converging smooth faces and operatively connected with the gearing and arranged to be actuated thereby into active position to move said cutting means outwardly and into released position to permit retraction of the cutting means, alternately, and means connected to the body for rotating the same.

5. A pipe severing device adapted to cut by rotation and shaped to be inserted into a pipe in a well to be cut and comprising an anchor, a cutter body on the anchor, a gear upstanding from the anchor and fixed against rotation relative to the anchor, the body being rotatable relative to the anchor, a train of gearing housed within the body and in operative connection with said gear whereby said train will be driven upon rotation of the body relative to the anchor, cutting means associated with the body and movable outwardly into cutting relation with the pipe, means normally acting to retract the cutting means into active position, an actuator operatively connected with one gear of the train and arranged to be reciprocated longitudinally of the body thereby and having a smooth tapering face effective to move the cutting means outwardly when the actuator is moved in one direction and to permit retraction of the cutting means when the actuator is moved in another direction.

ROBERT D. BRANNON,
HALL G. MOORE.
